UNITED STATES PATENT OFFICE.

WILBUR L. SHEPARD, OF ELMWOOD, AND EDWARD A. BEALS, OF HARTFORD, CONNECTICUT.

LOCOMOTIVE.

1,393,402.

Specification of Letters Patent. Patented Oct. 11, 1921.

Application filed October 14, 1919. Serial No. 330,645.

To all whom it may concern:

Be it known that we, WILBUR L. SHEPARD and EDWARD A. BEALS, citizens of the United States, residing at, respectively, Elmwood and Hartford, in the county of Hartford and State of Connecticut, have invented certain new and useful Improvements in Locomotives, of which the following is a specification.

10. This invention relates to what we shall for convenience term a "locomotive". We say, "for convenience", owing to the fact that the invention when incorporated in a machine such as a locomotive, is of particular utility. 15. It is of course clear that the invention may be embodied in other connections, of which traction and stationary engines are merely two of several illustrations. Probably the primary motive of the invention, is the provision of simple and effective means by which heat can be conserved. It is a matter of fact that at certain times, especially on an exceedingly cold day, the efficiency of a locomotive or engine of the present type, 20 is much lowered; our principal aim is to eliminate as far as practicable this great drawback, which we are enabled to accomplish without adding appreciably to the weight or otherwise complicating the machine. 25 Another object we have in view is the utilization of what is ordinarily waste heat in the carrying into effect of our aims. It is possible that all the features of the invention may not be present in any one case; 30 that is they may be employed jointly or individually.

In the drawings accompanying and forming part of the present specification we have shown somewhat in detail, one of the several 40 forms of embodiment of the invention which to enable those skilled in the art to practise the same, will be set forth fully in the following description. We are not restricted to this particular disclosure; we may in fact 45 depart therefrom in several respects within the scope of the invention defined by the claim following said description.

Referring to said drawings:

Figure 1 is a longitudinal, central sectional side elevation of a locomotive involving the invention.

Fig. 2 is a rear view of an injector and certain adjunctive parts.

Fig. 3 is a vertical section on the line 3—3

of Fig. 2 looking in the direction of the 55 arrows.

Fig. 4 is a cross section on the line 4—4 of Fig. 1 also looking in the direction of the arrows.

Like characters refer to like parts throughout the several views which are on somewhat different scales.

As we have already observed it is within the bounds of possibility that the features of the invention may be employed with advantages in many different ways, having already made it clear that the title selected, is merely for convenience and for the further fact that the invention is of prime utility in such a use, which is illustrated somewhat fully in the drawings.

The locomotive shown is denoted in a general way by 2 and its tender by 3, although merely the forward portion of the latter appears. The locomotive includes in its structure a boiler as 4 and back of the same is the pendant fire box 5 under which is the ash pit 6 as quite common. The boiler 4 is provided with the water spaces 7 and the tubes 8 through which pass the products of combustion from the fire box 5 to heat the water in said water spaces 7 as is usual. This structure need be but briefly described and it will be obvious that the invention does not necessarily concern the same.

It is a matter of fact as already virtually observed, that the efficiency of a locomotive is seriously affected in cold and wintry weather to such an extent in fact as tests have proven, that it is lowered to a very small point, this applying to the fire also. This is one of the objections we overcome. This is accomplished as illustrated by a jacket such as that denoted in a general way by 9. This jacket incloses partly or completely the boiler 4, its front end being connected with the smoke bonnet 4' of the boiler smoke space or interval being designated by 11. There may be if desired and as shown, struts or braces 12 between the boiler and jacket.

The rear end portion of the jacket or shell 9, has depending extensions 13, 14 and 15, the extension 13 being in front of and spaced from the front of the fire box 5 and ash pit 6 respectively and the side extensions 14 and 15 being laterally spaced from the corresponding portions of said fire box and ash

2
pit. By such jacketing of the boiler and the fire box we are enabled to adequately guard against the temperature-lowering effects of air blasts such as are invariably present in cold and snowy weather. While the complete jacketing of the boiler and the fire box and ash pit are desirable it may not be always necessary that the several portions be thus jacketed. For example in some cases it may be necessary to merely jacket the boiler while in others the fire box and the ash pit.

The waste gases and products of combustion are generally discharged at the front end of a locomotive. We prefer that these be led off at the rear portion or as nearly as practicable the rear end; certainly back of the front end. In this way we utilize these waste gases for increasing the efficiency of the boiler as will be hereinafter set forth.

The space 10 at the front of the boiler 4 serves conveniently as a receiver for an injector of proper kind, that denoted in a general way by 16 meeting our conditions. Said injector is of annular or circular, tubular or hollow form, being located within the space 10. The injector receives its hot agent, in the present case steam, in the form of exhaust from the cylinders 17. It has as shown a base or foot 18 resting on the bottom of said space 10, said base being secured rigidly in position in some convenient manner. The base or foot of the injector is connected by passage means such as denoted in a general way by 19, with the exhaust ports of the two cylinders 17 in view of which circumstance the exhaust steam from said cylinders, can pass by way of said passage means 19 up into the interior of the injector 18. Said injector or more properly its body is furnished with a series of rearwardly-directed annularly-arranged nozzles

20 which extend into the space 11 so that the exhaust steam can be directed into said space and can pass rearwardly, circulating 45 around the boiler 4 and also at opposite sides of the fire box 5 and ash pit 6 respectively, ultimately passing to atmosphere by way of a stack as 20' situated as noted, at the rear end of the jacket 9 and extending 50 through the roof of the cab 21.

A locomotive is usually equipped with air-brakes, and the means by which energy is ordinarily derived to effect the operation thereof, is obtained from an air pump as 22 55 driven by a steam motor as 23. The exhaust from this motor 23 passes into the pipe 24 which terminates at its discharge end in a ring 26 located in the lower end portion of the stack 20'. Thus this exhaust steam from the air brake motor is utilized 60 for promoting the draft.

The space 11 is closed at the rear by the wall 30, extending between the boiler 4 and the jacket 9. This wall has openings normally closed by the doors 31 by opening which the said space may be cleaned when desired, as by blowing steam or air through the space from either end of the boiler.

What we claim is:

The combination in a steam engine, comprising a boiler, a jacket around and spaced from the boiler, and means for causing the exhaust steam from the engine to pass along said space and at the same time to cause the 75 waste gases of the boiler to travel said space.

In testimony whereof we affix our signatures in the presence of two witnesses.

WILBUR L. SHEPARD.
EDWARD A. BEALS.

Witnesses:

MARGARET T. DENNIS,
HEATH SUTHERLAND.
